UNITED STATES PATENT OFFICE.

JACOB G. WHITLATCH AND OSCAR R. WILLIAMSON, OF IOWA FALLS, IOWA.

MUD DRUM.

Application filed October 14, 1920. Serial No. 416,869.

To all whom it may concern:

Be it known that we, JACOB G. WHITLATCH and OSCAR R. WILLIAMSON, citizens of the United States of America, and residents of 5 Iowa Falls, Hardin County, Iowa, have invented a new and useful Mud Drum, of which the following is a specification.

The object of this invention is to provide improved means for removing sediment such 10 as mud from the interior of a steam boiler and water leg thereof where such construction obtains.

A further object of this invention is to provide an improved construction for a 15 mud drum and its attachment to a steam boiler whereby sediment may accumulate continuously from said boiler in said drum and be discharged from said mud drum on occasion.

20 A further object of this invention is to provide an improved construction for mud drums whereby the water contained therein is maintained at a high temperature to the end of establishing and supporting a circulation of water through the mud drums 25 from and to the boiler.

Our invention consists in the construction, arrangement and combination of elements hereinafter set forth, pointed out in our 30 claims and illustrated by the accompanying drawing, in which—

Figure 1 is a side elevation of a boiler of conventional type showing one of the mud drums attached thereto in position for practical use. Figure 2 is an elevation partly in section of the mud drum on an enlarged scale, showing the heating coil arranged therein. Figure 3 is an elevation of one 40 end and Figure 4 an elevation of the opposite end of the mud drum, various pipes being shown in section.

In the construction and application of the devices as shown the numeral 10 designates a steam boiler having a water leg 11 and a dome 12, all of conventional type. An injector 13, also shown conventionally, is mounted on one side of and communicates with the boiler 10 in a common manner. The mud drum is constructed primarily of 50 a metal cylinder 14 and heads 15, 16 on opposite ends thereof, which cylinder and heads are imperforate and connected in a water-tight manner except as hereinafter provided. The mud drum is located adjacent to and alongside of the lower portion 55

of the water leg 11 and lies wholly in a plane below the bottom of the water in said water leg, which bottom is indicated by the dotted line 17. A pipe 18 communicates at one end with one end of the water leg adjacent to and above the water line 17 and communicates at the other end with the interior of the mud drum through a hole 19 in the upper portion of the head 15. A valve 20 is arranged in and controls the 60 passage through the pipe 18. A pipe 21 communicates at one end with the opposite end of the water leg 11 adjacent to and above the line 17 and communicates at its other end with the interior of the mud drum 65 through a hole 22 in the lower portion of the head 16. A valve 23 is mounted in and controls the passage through the pipe 21. A discharge pipe 24 communicates with and leads from the interior of the mud drum 70 through a hole 25 in the lower portion of the head 15, and a valve 26 is mounted in and controls the passage through said discharge pipe. A steam coil 27 is mounted in the cylinder 14 and extends substantially 75 from end to end thereof. One end portion of the steam coil 27 communicates through a hole 28 in the head 15 with a steam pipe 29 leading from the dome 12 and a valve 30 is mounted in said steam pipe and controls 80 the passage therethrough. The opposite end of the steam coil 27 communicates through a hole 31 in the head 16 with one end of a steam pipe 32, the opposite end of said steam pipe communicating with the injector 85 90 95 100 105 110

In practical use of the boiler the valve 26 is closed and the valves 20 and 23 are opened and sediment gravitates to the line 17 of the water leg and through the pipes 18 and 21 into the mud drum. When the injector 13 is used to supply feed water to the boiler in the common way, the valve 30 is opened and live steam is taken from the dome 12 through the pipe 29, coil 27 and pipe 32 for the operation of said injector. The flow of steam through the coil 27, during the operation of the injector, raises the temperature of the water in the mud drum above that of the water in the bottom of the leg 11 to the end of establishing a circulation of water as follows: from the leg through the pipe 21, mud drum and pipe 18 to the leg, thus producing a current and agitation of the water in the leg tending to

carry off sediment therefrom into the mud drum where it settles on account of the altitude of the hole 19 relative to that of the hole 22. After the injector has been used and 5 the valve 30 is closed, the valve 20 also is closed and the valve 26 is opened. The head of water in the boiler 10 and leg 11, augmented by whatever steam pressure may obtain in the boiler, is exerted through the 10 pipe 21 on the contents of the mud drum and, owing to the location of the holes 22 and 25 in substantially the same plane, a current is established longitudinally of the cylinder 14 between the pipes 21 and 24 to 15 the end of driving the sediment and water out of the mud drum through the discharge pipe, the current traveling the length of the drum and in the direction of the discharge pipe.

20 Repeated experiment has demonstrated the certainty of the operation as above described and the efficacy of such operation in removing sediment from the boiler, water leg and mud drum.

25 When elements above described are employed on a steam boiler the operation of depositing sediment in the water leg and causing it to filtrate through the pipes 18 and 21 into and become deposited on the 30 bottom of the mud drum is facilitated by agitation and circulation of the water, when the injector steam or live steam heats the water above the normal in the mud drum. Repeated experiment has demonstrated that substantially all of the sediment contained in the feed water is deposited in the mud drum during the normal use of the 35 steam boiler and that said sediment may be and is discharged from the mud drum during an operation as above described.

We claim as our invention—

1. The combination with a steam boiler of a mud drum located below the lowermost water line therein, valve controlled communications between opposite ends of said mud drum and said boiler adjacent to the lowermost water line thereof, said communications differing in altitude in respect to opposite ends of said drum, means for raising the temperature of water in the mud drum consisting of a steam coil located within said drum, a steam dome on the boiler, a valve controlled pipe communicating between said dome and one end of said coil, a return steam pipe communicating between the opposite end of said coil and said boiler at a point below the dome thereof, and means of discharge from said mud drum. 45 50 55

2. A mud drum formed of a recumbent cylinder and end closures thereon, a steam coil in said drum, a pipe extending from one end of said coil through one end of said drum and adapted to communicate with a steam dome, another pipe leading from the opposite end of said coil through the opposite end of said drum and adapted to communicate with a boiler below said dome, pipes communicating with and leading from opposite ends of said drum, at different altitudes and adapted to communicate with the lowermost portion of said boiler in substantially the same plane, valves on said pipes, and a valved discharge pipe communicating through one end of said drum with the lowermost portion of the cylinder. 60 65 70 75

Signed at Iowa Falls, in the county of Hardin and State of Iowa, this 27th day of Mch., 1920.

OSCAR R. WILLIAMSON.
JACOB G. WHITLATCH.
